UNITED STATES PATENT OFFICE.

ASA B. COOLEY, OF HUBBARD WOODS, ILLINOIS, ASSIGNOR TO MONTGOMERY WARD & CO., INCORPORATED, OF CHICAGO, ILLINOIS, A CORPORATION OF ILLINOIS.

DESIGN FOR A TIRE.

Application filed December 23, 1925. Serial No. 15,833. Term of patent 14 years.

To all whom it may concern:

Be it known that I, ASA B. COOLEY, a citizen of the United States, residing at Hubbard Woods, in the county of Cook and State of Illinois, have invented a new, original, and ornamental Design for Tires, of which the following is a specification, reference being had to the accompanying drawings, forming part thereof.

In the drawings:—

Fig. 1 is a plan view of a part of an automobile tire embodying the present invention, and

Fig. 2 is a cross section on the line 2—2 of Fig. 1.

I claim:—

The ornamental design for a tire substantially as shown.

ASA B. COOLEY.
